1

This invention of improvements relating to looms for weaving tufted pile fabrics refers to spool Axminster carpet looms and in particular to the mechanism for controlling the unwinding of warp yarn from a beam during its passage to the shed-forming mechanism of a loom.

The invention has for its object the provision of electrically operated stop motion means brought into operation when the yarn beam let-off motion fails to act, whereby to bring about immediate stoppage of the loom.

In a spool Axminster carpet loom, yarn to form the chain warp and yarn to form the stuffer-warp are led from the respective beams around a number of shafts in its passage to the shedding mechanism.

In the case of yarn to form the chain warp the yarn is led from the beam first around a guide shaft, then around a second shaft rotatably mounted at the rear of the loom frame and thence around a further shaft journaled in brackets mounted fast on the second-mentioned shaft. This third shaft, hereafter referred to as the chain-warp shaft, is adapted to have a rocking movement relatively to said second shaft and is under the influence of weights, whereby to maintain a uniform constant tension on the chain warp.

The beam, hereafter referred to as the chain-warp beam, is controlled by a let-off motion of the positive type operated by a worm engaging with a worm wheel on the beam shaft and operating by a pawl-and-ratchet mechanism. Interposed between the ratchet and the pawl is a flat plate pivoted on the worm shaft and adapted when moved forward to lift the pawl out of engagement with the teeth of the ratchet.

The said plate is operatively connected to the aforesaid chain-warp shaft, whereby when the chain-warp shaft is rocked in a direction towards the front of the loom under the pull of the chain-warp as the yarn is drawn forward by the loom take-up motion, the angular displacement of the chain-warp shaft causes said plate to be moved to permit the pawl to engage the ratchet wheel of the let-off motion, whereby a certain amount of chain-warp yarn is allowed to be wound off the beam, the chain-warp shaft returning to initial position under the influence of the before-mentioned weights maintaining a constant tension on the warp.

Located adjacent to the chain-warp beam is a further beam, hereafter referred to as the stuffer-warp beam. Yarn from the stuffer-warp beam is led first around a guide shaft and then around

5 a further shaft, hereafter referred to as the stuffer-warp shaft, which is journaled in brackets mounted fast on the first-mentioned guide shaft and is adapted for rocking movement about said guide shaft in similar manner to the chain-warp shaft. However, as the stuffer warp is not shedded, but merely passes straight through to the fabric, the extent of rocking movement of the stuffer-warp shaft is not so pronounced as that of the chain-warp shaft. The stuffer-warp shaft is also influenced by weights, whereby to maintain a constant tension on the stuffer warp. The let-off motion of the stuffer-warp beam also acts in similar manner to that of the chain-warp beam.

10 If, for any reason, the chain warp let-off motion fails to function, the take-up motion exerting a pull on the chain warp will rock the chain-warp shaft beyond its usual limit of movement until it is stopped by abutment against the adjacent stuffer-warp shaft and, as the let-off motion will not allow further yarn to be drawn off the chain-warp beam, the next movement of the take-up motion puts a considerable strain on 15 the chain warp, frequently resulting in breakage of the chain warp.

Similar conditions apply on failure of the let-off motion of the stuffer-warp beam.

20 To avoid this happening, I provide according to the invention an electric stop motion device adapted for operation by either the chain-warp shaft or the stuffer-warp shaft, whereby should the let-off motion fail to function properly, the loom is brought to a standstill before any damage can result.

According to a practical embodiment of the invention, there is secured on the loom frame and adjacent to one end of the rocker shaft carrying the movable chain-warp shaft, an adjustable contact insulated from the loom and forming one terminal of a low-voltage electrical circuit, the other terminal of which is formed by any metallic part of the loom.

45 A similar insulated contact in the same low-voltage circuit may be secured to the loom frame adjacent to one end of the movable stuffer-warp shaft. Preferably, however, a single insulated contact plate is used to serve for both shafts.

Secured to the end of the chain-warp rocker shaft is a metal plate or arm carrying a resilient contact terminal in register with the first-mentioned insulated terminal and forming a co-operating terminal in the low-voltage electrical circuit.

50 A similar plate with a resilient contact termi-

nal is secured to the end of the stuffer-warp rocker-shaft.

In the normal working of the loom, the let-off motion allows a predetermined length of chain warp to be drawn off from the beam; this amount is usually slightly in excess of the amount taken by the take-up motion and correct tension is maintained on the warp by the weighted movable shafts.

When the warp is drawn forward by the take-up motion, the chain-warp shaft is rocked about its pivot to a certain degree under the pull of the chain-warp, but the respective electrical terminals do not make contact and the loom continues working.

If, however, the let-off motion should fail to function, the chain-warp shaft would be rocked to an undesirable extent about its pivot and this extra movement would bring the resilient contact terminal on the rocker shaft into engagement with the fixed contact terminal provided on the loom frame and so complete the aforesaid low-voltage circuit. Completion of said circuit serves to energise a relay, which in turn operates the starter to break the electric circuit of the driving motor and bring about stoppage of said motor, whereupon the loom is brought to a standstill before any damage is sustained.

Similar conditions apply in regard to the stuffer-warp shaft.

The invention will now be described with the aid of the accompanying drawings, in which only so much of the carpet loom is shown as is necessary for a clear understanding of the invention.

In the drawings, Fig. 1 is a fragmentary end view showing the invention applied to a spool Axminster carpet loom; Fig. 2 is a fragmentary vertical sectional view through the line II-II of Fig. 1; Fig. 3 is a diagram of the electrical circuit of the electric stop motion; Figs. 4 and 5 are diagrammatic views of a detail part later to be described.

The same reference characters indicate corresponding parts in the several figures of the drawings.

Referring to Figs. 1 and 2, 10 indicates the chain warp shaft journaled at opposite ends in brackets, one of which is indicated at 11, fast on a shaft 12 journaled at opposite ends in bearings, one of which is indicated at 13, in the frame 14 of the loom. 15 indicates a guide shaft secured at opposite ends in bearings, one of which is indicated at 16, in the loom frame 14. 17 indicates the chain warp which is led from a chain warp beam, not shown, around the guide shaft 15, around the rocker shaft 12, thence over the chain warp shaft 10 to the loom take-up motion, not shown. The direction of traverse of the chain warp is indicated by the arrow points X-X.

The chain warp shaft 10 is under the influence of weights, not shown, attached to the rocker shaft 12, whereby the chain warp shaft tends to rock in the direction indicated by the arrow 1, Fig. 1, so maintaining the chain warp 17 in constant tension.

18 indicates the stuffer warp shaft journaled at opposite ends in brackets, one of which is indicated at 19, fast on a rocker shaft 20, journaled at opposite ends in bearings, one of which is indicated at 21, in the loom frame 14.

22 indicates the stuffer warp which is led from a stuffer warp beam, not shown, around

the rocker shaft 20, over the stuffer warp shaft 18 and to the loom take-up motion, not shown. The direction of traverse of the stuffer warp 22 is indicated by the arrow points Y-Y, Fig. 1.

The stuffer warp shaft 18 is under the influence of weights, not shown, on a rod 23 suspended from the hook-shaped end 24 of a swan-necked arm 25 forming an extension of the bracket 19, whereby the stuffer warp shaft 18 tends to rock in the direction indicated by the arrow 2, Fig. 1, so maintaining the stuffer warp 22 in constant tension.

Secured to the loom frame 14 is an adjustable contact plate 26 insulated from the loom frame 14 by a block 27 of insulating material interposed between the plate 26 and the loom frame 14. The plate 26 is secured to the frame 14 by screws 28 penetrating insulated bushes 29 inserted in holes in the plate 26 between the nuts 30 of the screws 28 and the contact plate 26. 26^a indicates an electrical lead secured at one end to the contact plate 26 by a screw 26^b and at the opposite end to the transformer of the electric stop motion device, later to be described.

As before stated, the contact plate 26 forms one contact in a low-voltage electrical circuit, the other terminal of which is formed by any metallic part of the loom frame 14, through the medium of one or other of two contact terminals carried by metal plates or arms on the respective rocker shafts of the loom.

Secured to the end of the rocker shaft 12 is a metal arm or plate 31 carrying a resilient terminal screw 32 in register with the contact plate 26 and forming a co-operating terminal in the low-voltage circuit of the electric stop motion.

Secured to the end of the rocker shaft 20 is a further metal plate or arm 33 carrying a resilient terminal screw 34 in register with the contact plate 26 and also forming a co-operating terminal in the said low-voltage circuit. Each terminal screw 32, 34 is normally held in advanced position by a spring interposed between the head of the respective screw and the respective plate 31 or 33.

As previously described, if the let-off motion should fail to function, the chain warp shaft 10 would be rocked to a greater extent than normal, due to the pull of the chain warp and this extra movement would bring the terminal 32 into contact with the contact plate 26 and complete the aforesaid low-voltage circuit to bring the electric stop motion into operation.

Similarly, if the stuffer-warp shaft 18 should move to an undesirably greater extent, the terminal 34 would be moved into contact with the contact plate 26 to complete the aforesaid low-voltage circuit to bring the electric stop motion into operation.

The sequence of operations of the electric stop motion will be described with reference to the diagram shown in Fig. 3, in which B indicates a transformer for low (safe) voltage; C indicates a trip relay with one normally closed contact indicated at C¹; D indicates a relay with two normally open contacts D¹, D²; E indicates a trip contact on the loom; F indicates a change-over push unit actuated by the loom starting handle, having four terminals, F¹, F², F³ and F⁴; G indicates a reset button on the loom; and H indicates a signal lamp.

The operation of the electric stop motion is as follows:

With the loom running normally, all the con-

tacts and relays are as shown in the diagram, Fig. 3.

When the chain-warp shaft 10, or the stuffer-warp shaft 18, is moved unduly and the terminal 32, or the terminal 34, makes contact with the contact plate 28 to close the low-voltage electric circuit, i. e., making contact at E, and thus energising the relay coil D and closing contacts D¹, D², contact D¹ provides an alternate path for electric current through the relay coil D, making the relay coil D self-retaining and now independent of the contact at E. The contact D² being closed provides a circuit through the contacts F¹, F² and relay coil C, thus breaking contact C¹ which causes the circuit to the electro-motor to be opened automatically, and de-energises a solenoid on the loom, whereby to trip the starting handle.

The starting handle, which is spring-loaded, thus returns to the "off" position and in so doing releases the clutch between the electro-motor and the loom and applies a mechanical brake, at the same time also releasing the change-over push unit F, breaking contact between F¹ and F² and bridging F³ and F⁴.

The relay coil C is now de-energised and C¹ returns to normal closed position. An alternative circuit then flows through contacts F³, F⁴, lamp H and contact D¹, thus indicating the cause of the stoppage.

The driving motor can be switched on if required and the loom "inched" at the operator's will, but, if the starting handle is moved to full "on" position before removal of the cause of stoppage, the stop-motion will again act.

Having rectified the cause of the stoppage, the operator can then press the re-set button G, and the loom is again ready for running.

The means for moving the starting handle quickly from "on" position to "off" position are shown diagrammatically in Figs. 4 and 5.

Referring to Figs. 4 and 5, 35 indicates the starting handle shown in the "on" position in a notch 36 in a quadrant 37, see Fig. 5. 38 indicates a solenoid carried in suitable position on the loom. Connected by a swivel 38 to the core 40 of the solenoid 38 is a bell-crank lever 41, the opposite end of which is connected to an adjustable connecting rod 42. The connecting rod 42 is connected at its opposite end by a lever 43 to a knock-off lever 44 pivoted on the same shaft 45 as the lever 43, the free end of the knock-off lever 44 lying adjacent to the starting handle 35 when in the "on" position. When the stop motion is actuated as previously described, the solenoid 38 is de-energised, whereupon the core 40 drops and through the link 39 rocks the bell-crank lever 41 which in turn pushes the connecting rod in the direction of the arrow Z to rock the lever 43 and with it the knock-off lever 44 which, moving quickly forward under the influence of a spring 46 in operative association with the connecting rod 42, knocks the starting handle 35 out of the notch 36.

The starting handle 35, which is spring-influenced, moves rapidly to the "off" position and releases the driving clutch between the electro-motor and the loom and applies a brake to bring the loom to a standstill.

I claim:

1. The combination with a yarn beam let-off motion for a spool Axminster carpet loom having a frame, a driving motor, a chain-warp shaft

and a rocker shaft therefor, a stuffer-warp shaft and a rocker shaft therefor, a clutch, a starting handle and a brake, of electric stop motion means embodying a low voltage electric circuit, said means including a fixed metal contact plate, an insulation piece interposed between said metal plate and the loom frame, insulation bushes in said metal plate and screws screwing through said insulation bushes to secure said metal plate to the loom frame, whereby the metal plate is held to but insulated from the loom frame, the metal plate forming one contact terminal in the low-voltage circuit of the electric stop motion means, a metal plate secured to the end of the rocker shaft of the chain-warp shaft of the loom, a contact terminal screw slidably mounted in said last-mentioned plate, a spring surrounding said screw between the head of the screw and the said metal plate, a further metal plate secured to the end of the rocker shaft of the stuffer-warp shaft of the loom, a contact terminal screw slidably mounted in said last mentioned plate, and a spring surrounding said screw between the head of the screw and the metal plate, either of said terminal screws serving as the second terminal in the said low-voltage circuit.

2. The combination as claimed in claim 1, further including a spring influencing the starting handle for operating the clutch to the driving motor, a spring for returning said starting handle to the "off" position, a notched quadrant, a solenoid, a bell-crank lever connected at one end to said solenoid, a connecting rod attached at one end to the end of the bell-crank lever remote from the solenoid, a spring attached at one end to said connecting rod and at its opposite end to the loom frame, a pivoted knock-off lever positioned adjacent to said starting handle when said starting handle is in the "on" position in the quadrant, and a lever between said connecting rod and said knock-off lever, whereby when the let-off motion fails to function so permitting undue movement of the chain-warp shaft or the stuffer-warp shaft, the terminal on and movable with the respective rocker shaft of the chain-warp shaft and the stuffer-warp shaft being brought into contact with the fixed terminal on the loom frame so completing the low-voltage electric circuit of the electric stop motion means, whereby the solenoid is de-energised and through the lever system the knock-off lever is caused to knock the starting handle out of the notch in the quadrant, whereupon the starting handle under the influence of its spring moves quickly to the "off" position to release the driving clutch and apply the brake to bring the loom to a standstill.

3. The combination as claimed in claim 1, in which the low-voltage electric circuit includes a transformer for low voltage, a trip relay with one normally closed contact, a relay with two normally open contacts, a change-over push unit actuated by the loom starting handle, having four terminals, a re-set button on the loom, and a signal lamp.

I. B. BASSINDALE.
